Primary Examiner — Karen S Acker

(57) **CLAIM**

The ornamental design for a fireplace argento, as shown and described.

DESCRIPTION

FIG. 1 is a front perspective view for a fireplace argento showing my new and original design;

FIG. 2 is a front elevation view for the fireplace thereof;
FIG. 3 is a right side elevation view thereof; and,

FIG. 4 is a left side elevation view thereof.

The broken lines showing of environment are for illustrative purposes only and form no part of the claimed design.

The bottom, top and back sides of the fireplace argento form no part of the claimed design. The broken line and the space within the broken line represent unclaimed environmental subject matter.

1 Claim, 4 Drawing Sheets

FIG. 1

FIG. 2

FIG. 3

FIG. 4
